*Primary Examiner—B. J. Bullock
Attorney, Agent, or Firm—Scully, Scott, Murphy & Presser***[57] CLAIM**

The ornamental design for a garment hanger, as shown and described.

DESCRIPTION

FIG. 1 is a front elevational view of my new design;
 FIG. 2 is a rear elevational view of FIG. 1;
 FIG. 3 is a left end elevational view of FIG. 1;
 FIG. 4 is a right end elevational view of FIG. 1;
 FIG. 5 is a top plan view of FIG. 1;
 FIG. 6 is a bottom plan view of FIG. 1; and
 FIG. 7 is a front elevational view of a second embodiment
 of the design of FIG. 1, the only difference being the upper
 portion of the hook.
